Nov 11, 1879

NO. 11,506

UNITED STATES PATENT OFFICE.

ALBERT HART, OF HARTFORD, CONNECTICUT, ASSIGNOR TO THE WILLIAM ROGERS MANUFACTURING COMPANY, OF SAME PLACE.

DESIGN FOR HANDLES FOR TABLE-CASTERS.

Specification forming part of Design No. **11,506**, dated November 11, 1879; application filed October 18, 1879.
[Term of patent 3½ years.]

To all whom it may concern:

Be it known that I, ALBERT HART, of Hartford, in the county of Hartford and State of Connecticut, have originated and invented a new and useful Design for a Handle for Table-Casters; and I do hereby declare that the following is a full, clear, and exact description thereof, reference being had to the accompanying drawing, forming a part of this specification.

The base or lower end of the handle, where it fits upon the caster, is usually formed with an elliptical bulge or ring, *a*, whence the stem *b* of the handle extends upward in straight but converging lines to a similar ring or bulge, *c*, and from the upper side of this extends upwardly the somewhat triangular loop *d*, which forms the handle proper. The sides or surface of this loop may be ornamented, and may be made lozenge-shaped in cross-section, or in any desired form, and it may at the point, *e*, of its greatest width, have any suitable ornamenta-

tion to give a pleasing and attractive effect. The upper part, *d'*, of the loop is rounded or arched, and its surface may be ornamented. Centrally on the top of the arch, and in line with the stem of the handle, is placed the crown or crown-ornament *h*. Near the base of the loop, inside, and just above the point where it springs from the top of the stem, is the ornamentation *i*, formed of leaves and fruit, or by any other suitable design.

I claim—

The table-caster handle above described, consisting of a stem having a loop-handle surmounted by a crown, substantially as set forth.

In testimony that I claim the foregoing as my own I affix my signature in presence of two witnesses.

ALBERT HART.

Witnesses:

F. WILLSON ROGERS,
EDWARD S. WHITE.
